DESIGN FOR A DRESS

Austin J. Bono, Revere, Mass., assignor to Fitwel Dress Co., Inc., Boston, Mass., a corporation of Massachusetts

Application November 8, 1941, Serial No. 104,094

Term of patent 7 years

To all whom it may concern:

Be it known that I, Austin J. Bono, a citizen of the United States and resident of Revere, in the county of Suffolk, State of Massachusetts, have invented a new, original, and ornamental Design for a Dress, of which the following is a specification, reference being had to the accompanying drawing, forming part thereof.

Fig. 1 is a front elevation of a dress showing my new design.

Fig. 2 is a side elevation; and
Fig. 3 is a rear elevation.

I claim:

The ornamental design for a dress, as shown.

AUSTIN J. BONO.
